UNITED STATES PATENT OFFICE.

BURTON W. KENDALL, OF NEW YORK, N. Y., ASSIGNOR TO WESTERN ELECTRIC COMPANY, INCORPORATED, OF NEW YORK, N. Y., A CORPORATION OF NEW YORK.

SYNTHESIS OF COMPOUND TONES BY VACUUM-TUBE OSCILLATORS.

Application filed November 20, 1917. Serial No. 202,938.

To all whom it may concern:

Be it known that I, BURTON W. KENDALL, a citizen of the United States, residing at New York, in the county of New York and 5 State of New York, have invented certain new and useful Improvements in Syntheses of Compound Tones by Vacuum-Tube Oscillators, of which the following is a full, clear, concise, and exact description.

10 This invention relates to vacuum tube oscillators, and more particularly to what are known as harmonic generators and to means for controlling the number and proportion of harmonics in the output of such 15 generators. The invention may have various applications in arts where it is desired to produce a periodically varying current having certain definite numbers and proportions of harmonics or a tone having certain definite numbers and proportions of harmonics. Such tones are used, for example, in music. As the production of such a tone is preceded 20 by the production of the current in a suitable circuit, which current produces the tone 25 by acting through a suitable translating device, this specification will deal more specifically with the production of tones, it being understood that the generic aspect of the invention contemplates production of the currents as aforesaid, either for the production 30 of tones or for other purposes.

It is well known that a musical note, such as produced by the human voice or instruments, consists of vibrations of some fundamental frequency, which we may denote by the symbol F , combined with one or more of a series of overtones or harmonics of frequency $2F$, $3F$, $4F \dots nF$. The musical quality or timbre of the note depends on the 35 number and relative intensity of these harmonic components, the note of some instruments containing chiefly odd harmonics and of others even harmonics, while others contain both odd and even members of the series. In general, however, the higher members of the series are of small intensity or wholly lacking.

It is known how to design and adjust a 40 thermionic oscillation generator so as to produce in the output circuit thereof, an oscillation of a fundamental frequency combined with a number of the harmonics thereof, the latter being present in appreciable amounts. The present invention consists, primarily, in

55 a means for and method of regulating the number of these harmonics and their relative intensities with respect to each other and the fundamental.

This is accomplished by the means shown in the accompanying drawings, wherein Fig. 60 1 represents diagrammatically a harmonic generator with the novel harmonic regulating means associated therewith; Figs. 2 and 3 represent two modified forms of harmonic regulating means for use with a harmonic 65 generator as in Fig. 1, the line $X-X$ indicating the corresponding points of junction at $X-X$ in Fig. 1; and Fig. 4 represents a series of groups of such anti-resonant 70 circuits as are found in Fig. 1.

75 Numeral 5 indicates an evacuated vessel or tube of the audion type, which, with its connections, functions as harmonic oscillation generator H , while A , A' represent similar vessels functioning as amplifiers. The tube 5 has its plate circuit arranged to feed back to the grid circuit through the coupled coils 9 of the plate circuit and 8 of the grid circuit. The path for the direct current in the plate circuit is through the coil 11 of high 80 inductance, resistance 12 and the plate battery 7. The direct current flowing there-through is practically constant and independent of the frequency of oscillation. The tuning condenser 10 is shunted around coil 85 9 and, by adjusting it, and using proper values of inductances 8 and 9 the oscillation frequency may be made any desired practical value. The oscillating currents do not pass through the coil 11 owing to its high 90 inductance and the resistance 12, but pass principally through the path containing the condenser 13 and inductance coil 14. The condenser 13 is of large capacity so that the 95 impedance of this path is largely due to the coil 14, the function of the condenser being only to prevent passage of direct current. The coil 14 is of somewhat low impedance to low frequencies and higher impedance to higher frequencies so that the voltage drop 100 for equal currents across 14 increases with the frequency. This apparatus constitutes the harmonic generator, the action of which is hereinafter described.

The voltage drop across coil 14 is the 105 source of grid voltage for the vacuum tube 6, which will thus have impressed upon it the fundamental and the various harmonics

in the same order of intensity. The tube 6 and its associated circuits constitute the amplifier A. The direct current output of amplifier A passes through resistance 16, induction coil 15 and plate circuit battery 17, while the circuit for the amplified alternating current passes through a large condenser 21 and a series of loop-resonant circuits 18, more usually known as anti-resonant circuits, each of which contains an adjustable condenser 19, adjustable inductance 20 and adjustable resistance 22. Each anti-resonant circuit may be short-circuited by a corresponding switch S.

18 Suppose the fundamental frequency of the oscillator H to be F and the harmonics 2F, 3F and 4F. The anti-resonant circuits 18 are made to be respectively loop-resonant or anti-resonant at frequencies F, 2F, etc., 20 one circuit being present for every harmonic desired in the output. Suppose resistances 22 are adjusted to zero and switches S are open. Each circuit 18 will present a high impedance to the harmonic component of 25 its own frequency and small impedance to other frequency components. This will result in all the components being impressed upon the grid-filament circuit of the amplifier A', as each anti-resonant circuit will 30 furnish a source of voltage of its own particular frequency. This input is amplified and, by means of transformer 24, of which the primary is in output circuit 23 of tube 26, is impressed upon a suitable translating 35 device as, for example, a receiver 25. The receiver 25 is intended to typify any suitable device or devices for translating electric energy into sound wave energy, such as an electro-magnetic or an electro-static receiver. If some frequencies preponderate, 40 their proportionate intensity may be lessened as, for example, by adjusting resistances 22 and thereby varying the impedance of circuits 18. In case it is desired to eliminate any frequency, the anti-resonant circuit corresponding thereto may be short-circuited by its corresponding switch S.

For efficient operation, the generator H should be overloaded, that is, the voltage 50 variation of the input should be sufficiently great so that the current variation of the output will cover a considerable range of the characteristic, extending upon curved portions thereof, thereby increasing the distortion, which, in general, increases the 55 amplitudes of the harmonic components. In general, the oscillator will as a result of its inherent nature assume this operating condition. The amplifier A', on the other 60 hand, should be only slightly loaded so that it will produce substantially no harmonics.

In Fig. 2 the anti-resonant circuits of frequencies F, 2F, 3F, 4F, are coupled to corresponding circuits, each containing an 65 adjustable condenser 28, a resistance 29 and

a coil 30, the latter being the means of coupling. The resistances 29 and the switches S serve similar functions to those in Fig. 1. The parts 23, 24, 25 and 26 are the same as in Fig. 1. In Fig. 3 the circuits 27 70 have resistances 31 connected across the condenser terminals. By adjusting these resistances both the functions of resistances 22 or 29 and switches S may be performed. The remaining elements correspond to 75 Fig. 1.

In Fig. 4 the circuits 18 are tuned to be anti-resonant at the respective frequencies F, 2F, 3F and 4F, the circuits 32 are tuned to be anti-resonant at another series of frequencies F_1 , $2F_1$, $3F_1$ and $4F_1$. An indefinite number of such series may be used, circuits 33 representing the last which are anti-resonant at frequencies F_n and the harmonics thereof. Then if frequency F corresponds to note C of the musical scale, F_1 to C#, F_2 to D, etc., it is possible to secure in receiver 25 any desired note of the chromatic scale of any desired quality. Switches S would normally be closed. Then suppose 80 it be desired to produce the note C with its first harmonic. By adjusting condenser 10 so as to cause the fundamental oscillations to be of the frequency F and simultaneously opening switches S, which shunt circuits 18 of frequency F and 2F, the desired tone 85 will be produced. In a similar manner any other fundamental note with any desired harmonic components may be caused to sound in receiver 25. 90

In lieu of the compound series of anti-resonant circuits in Fig. 4, the capacity, inductance and resistance of a single series, such as in Fig. 1, may be adjusted to be anti-resonant at one time to the note C and 105 its harmonics, at another time to the note C# and its harmonics, etc. It is not essential that the same harmonic generator H be used for all notes, as one may be used for one note, another for another, and so on. 110 The oscillations of several such tubes may be impressed at one time across the series of anti-resonant circuits, thus producing any desired combination of fundamental tones and their harmonics, or the outputs of several amplifiers A', each connected to a different series of anti-resonant circuits and harmonic generator may be impressed upon a receiving instrument 25. In such manner any combination of tones may be produced. The anti-resonant circuits are not limited to a series of F, 2F, 3F and 4F, 115 but may be extended to nF where n represents any desired integer. All electrical elements used, such as condensers, inductances, resistances, couplings and battery voltages are, for convenience, made adjustable, unless it would be obvious that no adjustment would be useful. If a certain tone and its harmonics be represented by 120 125 130

5 frequencies F , $2F$, $3F$, $4F$, $5F$, $6F$, etc., it will be noted that by eliminating the fundamental tone F and its odd harmonics, $3F$, $5F$, etc., there will be remaining the tone $2F$ and its harmonics $4F$, $6F$, etc. This would serve as a convenient method of securing tones of higher octaves with less multiplicity of apparatus. The harmonic generator and the parts to the left of the 10 line X—X in Fig. 1 are not in themselves new and no novelty is claimed therefor except in combination with other parts as hereinafter indicated. The generator typifies any suitable means for producing currents of suitable frequencies having harmonic components in suitable amounts.

The parts, combinations and methods inherent in the invention which are believed to be novel are defined in the appended claims.

What is claimed is:

1. The method of producing a desired complex electric wave which comprises continuously generating a voltage wave including a plurality of different frequency components of invariable amplitudes simultaneously produced, impressing said voltage wave upon an impedance path having large impedance to components which are to be 25 of large amplitude in the wave to be produced and having relatively small impedance to components which are to be of small amplitude in or absent from the wave to be produced, thereby selecting desired components and regulating their amplitude and utilizing the difference of potential across 30 said path for setting up the desired wave.

2. The method of producing a desired electric wave which comprises maintaining 40 a voltage containing all of the components of the desired wave and selecting therefrom appropriate proportions of the particular components necessary to produce the desired wave.

15 3. The method of producing a desired form of wave of alternating current which consists in passing a given complex wave through a system of circuits, adjusting each of said circuits to a desired value of impedance to a certain frequency component of said given wave and utilizing the sum of the differences of potential across said circuits as a source of potential for causing the desired wave.

55 4. The method of producing a desired form of wave of alternating current which consists in passing a given compound wave of current through a system of circuits, adjusting each of said circuits to a desired 60 value of impedance to a certain frequency component of said given wave, amplifying the sum of the differences of alternating potential across said circuits, and impressing the amplified summation voltage upon 65 a conductor.

5. The method of producing an alternating voltage having definite frequency components in definite proportions which comprises producing a sustained voltage wave having a plurality of different frequency 70 components of invariable amplitudes simultaneously produced and impressing the produced wave upon a conductor whose impedances to the different components are relatively proportioned to produce a difference of potential thereacross having the definite components in the definite proportions 75 which are desired.

6. Means consisting of a number of circuits arranged in series, one of which is substantially anti-resonant at one frequency 80 of current applied thereto and each of the others substantially anti-resonant at a multiple frequency thereof, and a device connected to the terminals of said series for 85 utilizing the voltage thereacross.

7. Means according to claim 6 in combination with a series of switches, each switch when closed forming a shunt around one of 90 said circuits.

8. The combination of claim 7 in which the device connected to the terminals of the series of circuits comprises an amplifier, the extreme ends of said series being connected 95 respectively to two input terminals of said amplifier.

9. A system comprising a number of circuits arranged in series, one of which is substantially anti-resonant at one frequency 100 of current applied thereto and each of the others substantially anti-resonant at a multiple frequency thereof, a one-way energy transferring device connected across the terminals of said series and an instrument associated with said device for producing 105 sound waves from electrical waves.

10. The combination of a series of anti-resonant circuits, one of which is anti-resonant at a certain frequency and another at a multiple of said frequency, a source of 110 electromotive force, means for impressing said force across the terminals of said series, an amplifier, means for impressing the potential difference across a desired one or more of said circuits upon said amplifier. 115

11. Means for producing a desired compound recurrent electrical current wave containing given components in desired proportions including means for generating a current wave containing said components in 120 other proportions, and means acted on by the energy of said generated current wave for regulating the proportions of the several components thereof to produce another current wave containing said components in 125 said desired proportions.

12. The combination of a series of anti-resonant circuits, one of which is anti-resonant at a certain frequency and another at a multiple of said frequency, a source of 130

- electro-motive force, means for impressing said force across the terminals of said series, a translating device, and means for impressing the potential difference across a selected 5 number of said circuits simultaneously upon said translating device.
13. A source of compound electromotive force each of whose components consist of a fundamental and harmonics, means for 10 simultaneously producing another electromotive force having selected components of said first mentioned electromotive force, and means for producing sound waves in accordance with the components of said second electromotive force.
14. A source for simultaneously producing an electromotive force wave having a large number of different frequency components of predetermined amplitudes, 15 means energizing said source to cause said source to continuously produce all of said components, means for simultaneously producing another sustained electromotive force comprising means for selecting desired components of said first mentioned electromotive force and varying their amplitudes to produce components having intensities of different relative proportions than in said first mentioned electromotive force, and 20 means for translating said second electromotive force into sound waves.
15. A series of groups of anti-resonant circuits, each group consisting of a series of circuits, each of said series of circuits consisting of a plurality of members one of 25 which is adjusted to anti-resonance at one frequency and another of which is adjusted to anti-resonance at a multiple frequency thereof.
16. A series of groups of anti-resonant circuits, each group consisting of a series of circuits, the first of said series of circuits containing members respectively anti-resonant at a frequency and harmonics thereof, 30 others of said series of circuits containing members respectively anti-resonant at a second frequency and harmonics thereof, said frequencies being related to each other as the vibration frequencies of two selected 35 tones of any musical scale.
17. In combination, a harmonic generator, means associated therewith for causing said generator to generate a plurality of fundamental frequencies, and means to produce from the various generated waves a combined wave having a fundamental frequency equal to one of said fundamental frequencies and selected proportions of harmonics thereof.
18. In combination, a harmonic generator, means associated therewith for causing said generator to generate a plurality of fundamental frequencies, and means to produce from the various generated waves 60 a complex note having a fundamental frequency equal to one of said fundamental frequencies and selected proportions of harmonics thereof.
19. In combination, a harmonic electrical generator, means to cause said generator to successively generate a plurality of fundamental frequencies and their respective harmonics, means to produce therefrom currents lacking a part of said harmonic frequencies, and means to translate the electrical energy of the said currents into sound waves.
20. An electrical system comprising electron discharge means, input terminals and an output circuit for said means, means comprising a plurality of tuned circuits each including an intensity regulating means for supplying a plurality of sets of audio frequency waves of selected intensity to said input terminals and a receiving device operatively related to said output circuit responsive to effects produced by said waves, whereby a compound tone of regulable pitch and timbre may be produced.
21. An electrical circuit comprising electron discharge means having a plurality of input terminals and an output circuit, means comprising a plurality of tuned circuits each including an intensity regulating means for simultaneously supplying a plurality of sets of audio frequency waves of selected intensity to said input terminals, and a receiving device electrically connected to said output circuit so as to be responsive to the effect produced in said circuit by 90 said sets of supplied waves, whereby a compound tone of regulable pitch and timbre may be produced.
22. A system comprising means for supplying a plurality of electromotive forces 105 each including a fundamental and one or more selected harmonics thereof, means for regulating the intensity of the fundamental and selected harmonics of said electromotive forces, means for establishing a space current, and means for varying said current in accordance with the resultant electromotive forces, whereby a compound wave having regulable properties may be produced.
23. A system comprising means for continuously producing a plurality of harmonic electromotive forces, a space discharge repeater, a receiver associated with said repeater and means for selectively applying 110 predetermined values of each of said electromotive forces to said repeater whereby a tone of any pitch and timbre may be produced in said receiver.
24. A system comprising an input conductor, a plurality of loop circuits serially connected there across, each loop circuit being tuned to a different frequency and a translating device connected across a plurality of said circuits.

25. A system comprising an input conductor, a series arrangement of loop circuits connected there across, each said circuit including a capacity element and an inductance element, a thermionic repeater, an input circuit for said repeater, said input circuit being connected across a plurality of said loop circuits.
26. The combination of a series of anti-resonant circuits one of which is anti-resonant at a certain frequency and others at a
- multiple of said frequency, a source of electric waves, means for impressing said waves across the terminals of said series, an amplifier, and means for impressing the potential difference across a desired one or more of said circuits upon said amplifier.

In witness whereof, I hereunto subscribe my name this 15th day of November A. D., 1917.

BURTON W. KENDALL.
